UNITED STATES PATENT OFFICE.

HORACE HILLYARD HASTINGS, OF TORONTO, ONTARIO, CANADA.

DESIGN FOR A TIRE.

Application filed June 10, 1921. Serial No. 476,580. Term of patent 14 years.

To all whom it may concern:

Be it known that I, HORACE HILLYARD HASTINGS, a subject of the King of Great Britain, and a resident of Toronto, in the Province of Ontario, in the Dominion of Canada, have invented a new, original, and ornamental Design for Tires, of which the following is a specification, reference being had to the accompanying drawing, forming part thereof.

In the drawings Figure 1 is a perspective view of a tire, showing my new design.

Figure 2 is a cross sectional view of the tire on the line A—A in Figure 1.

Figure 3 is a cross sectional view of the tire on the line B—B in Figure 1.

I claim:

The ornamental design for a tire, as shown.

HORACE HILLYARD HASTINGS.
